UNITED STATES PATENT OFFICE.

EDWARD R. IVES AND CHARLES A. HOTCHKISS, OF BRIDGEPORT, CONNECTICUT, ASSIGNORS TO IVES & WILLIAMS, OF SAME PLACE.

DESIGN FOR A HATCHET.

SPECIFICATION forming part of Design No. 24,056, dated February 19, 1895.

Application filed January 14, 1895. Serial No. 534,924. Term of patent 7 years.

To all whom it may concern:

Be it known that we, EDWARD R. IVES and CHARLES A. HOTCHKISS, citizens of the United States, residing at Bridgeport, in the county 5 of Fairfield and State of Connecticut, have invented and produced a new and original Design for Toy Hatchets; and we do declare the following to be a full, clear, and exact description of the same, reference being had to 10 the accompanying drawing, forming a part thereof.

This invention relates to a new design for a hatchet; and consists in the new configuration hereinafter described.

15 The figure is an elevation illustrating our novel design.

“a” denotes the blade of the hatchet; “b,”

the handle, and “c” a bust of a man formed upon the head of the hatchet which in the present instance is a likeness or conventional 20 representation of George Washington. Between the blade *a* and the bust *c* is a representation of neck clothing *d*.

What we claim is—

The design for a hatchet substantially as 25 shown and described.

In testimony whereof we affix our signatures in presence of two witnesses.

EDWARD R. IVES.
CHARLES A. HOTCHKISS.
